UNITED STATES PATENT OFFICE.

OMAR H. JEWELL AND WILLIAM M. JEWELL, OF CHICAGO, ILLINOIS.

CHEMICAL-FEEDER.

SPECIFICATION forming part of Letters Patent No. 423,773, dated March 18, 1890.

Application filed December 23, 1889. Serial No. 334,639. (No model.)

To all whom it may concern:

Be it known that we, OMAR H. JEWELL and WILLIAM M. JEWELL, citizens of the United States of America, residing at Chicago, in the county of Cook and State of Illinois, have invented certain new and useful Improvements in Water-Purifying Apparatus, of which the following is a specification, reference being had therein to the accompanying drawings.

10 This our invention relates to apparatus for purifying water by the admixture of chemicals and the subsequent filtering thereof; and it has for its object to provide, in combination with a filtering-tank, a chemical-feeder 15 that automatically will regulate the amount of chemicals admixed to be proportional with the amount of water forced through the filter; and with these objects in view our invention consists of the novel devices and combinations of devices hereinafter described, and 20 specifically claimed.

In the accompanying drawings, Figure 1 is a section of a chemical-feeder connected with the top of the filtering-tank, and Figs. 2 and 25 3 show an exterior view and section of a modified form of gravitating device for the automatic valve in such chemical-feeder.

Corresponding letters of reference in the several figures of the drawings designate like 30 parts.

The chemical-tank is put together of two sections M and M' and of the cover m, all secured together by bolts, and the section M' has to its bottom M³ a chamber M², for an oscillating valve N, angularly seated and pivoted at its upper end on a pin or trunnion o. This valve is inserted through a hole in bottom M³, which hole is closed by a screw-plug O. The feed-pipe P from the force-pump 35 connects with chamber M² in the rear of valve N, and the supply-pipe C of the filtering-tank A connects with chamber M², forward of the valve N, in such a manner that the water forced by the pump must pass under valve N before 40 it can enter pipe C and tank A. The valve N has an eyed arm n, coupled with the lower eyed end of a rod p, extended into a vertical pipe Q, screwed with its lower end into an opening in bottom M³, intermediate of valve 45 N and pipe C, and closed on top by cap q. The rod p has a cross-pin p', upon which is

seated a spiral spring r, extending into cap q, where it butts against the collar of a screw-rod R, projected through the screw-threaded hole in a boss of cover m, and also through a 55 hole in cap q, and having an eyed head for turning such screw-rod R, and thereby regulating the elastic resistance of spring r against valve N. The boss of cover m, tapped by rod R, is also exteriorly screw-threaded for a shell 60 s, screwed thereon, to cover and protect screw-rod R, which shell s must be removed for adjusting such screw-rod R.

To a nozzle in the side of cap q is coupled the casing t of a swinging check-valve T. 65

Intermediate of valve N and supply-pipe P is screwed into bottom M³ the casing U of a conical feed-valve u, the stem of which, being screw-threaded, is tapped through the gland of such casing, and thence is extended 70 through a stuffing-box v, secured to section M' of the tank, with a hand-wheel V mounted upon it, by which such valve u can be adjusted or entirely closed. The upper portion of valve-casing U is funnel-shaped for a 75 spherical gravity-valve W, finding its seat therein and being retained in such funnel by a cross-rod w. This valve W is for the purpose of preventing chemicals from entering the valve-casing.

The cover m of the receptacle is provided with a large opening closed by a cover S, which by means of a bow-piece y, pivotally secured to cover m, and by a clamp-screw Y, tapped through the center of such bow-piece, 85 is secured upon such opening, through which the chemicals are inserted.

Into one side of section M' of the chemical-receptacle is tapped a faucet Z, for discharging from such tank the water contained 90 therein after closing valve u.

The *modus operandi* of the entire apparatus is as follows, to wit: The chamber M M' being partly filled with chemicals (such as alum) and the valve u being opened to the 95 desired extent, the water forced in through pipe P being resisted by valve N, yieldingly depressed by spring r, a small portion of such water will enter the chamber through such valve u, will pass through the chemicals contained therein, dissolving a small amount thereof, and thence escaping under valve T.

and through pipe Q to intermix with the water passing under valve N before entering pipe C and tank A. By this device the force consequent from the amount of water passing under valve N will govern the amount of water passing through the opening of valve u to be of a like proportion with a more or less feed of water to be filtered, which proportion may be regulated for a stronger or weaker solution of chemicals proportional to such water by adjusting the tension of spring r and by opening the valve u more or less. This device, as will be readily seen, after being once adjusted will provide an automatic or self-regulating feed of chemicals to the water to be filtered to be of a steady uniform proportion to the amount of water passing through pipes P and C. With a reverse current the valves T and N will prevent water from entering the chamber M and M', and for emptying such tank for the purpose of cleaning and recharging with chemicals the valve u is closed and faucet Z is opened. The turbid water, after being thus intermixed with chemicals to render it limpid, enters through pipe C the tank A, when for filtering the valves d, h, and i are closed, and the water, after trickling through the filtering material in such tank and after separating therein from its impurities, will escape through strainer E into pipe G, that will conduct the water thus thoroughly purified into a proper reservoir ready for immediate use.

Instead of spring r, for resisting valve N of the chemical-receptacle, we can extend the pin o of valve N through a stuffing-box of chamber M², providing it with a crank-arm x, and can adjustably secure upon such crank-arm a weight X, for yieldingly holding the valve N to its seat, all as shown by Figs. 2 and 3, which device, however, we consider an equivalent to the spring previously described.

It will be readily seen that the arrangement of the chemical-feeder, when thus combined with a filtering apparatus, is simple and effective in its operations, and both combined form a very complete device for the desired purpose.

What we claim is—

1. The combination, with a filtering-tank, of the chemical-tank M, having to its bottom a chamber M², communicating with water-supply pipe P and through pipe C with the filtering-tank, and provided with valve N, interposed between pipes P and C and yieldingly held to its seat by either a spring or weight, an adjustable inlet-valve u, providing communication between chamber M² and the chemical-chamber behind valve N, and a vertical pipe Q with check-valve T, providing similar communication forward of valve N, all substantially as set forth, for the purpose specified.

2. The combination, with a filtering-tank, of the chemical-tank M, having to its bottom a chamber M² for a swinging valve N, yieldingly held to its seat by either a spring r or a weighted crank x and having connected the water-supply pipe P behind such valve N and the pipe C, leading into the filtering-tank forward of valve N, valve-easing U, provided with adjustable stop-valve u, providing communication between chamber M² and the interior of tank M, intermediate of valve N and pipe P, and pipe Q with check-valve T, providing similar communication intermediate of valve E and pipe C, all substantially as set forth, for the purpose specified.

In testimony whereof we affix our signatures in presence of two witnesses.

OMAR H. JEWELL,
WILLIAM M. JEWELL.
